(57) **CLAIM**

We claim, the ornamental design for a stand for television receiver, as shown and described.

DESCRIPTION

FIG. 1 is the front perspective view of a stand for television receiver showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof;

FIG. 7 is a bottom plan view thereof; and,

FIG. 8 is a rear perspective view thereof, as shown in a television environment.

The dot dash lines in the figures represent an unclaimed boundary line and form no part of the claimed design.

The broken lines illustrating portions of the stand for television receiver are for environmental purposes only and form no part of the claimed design.
